FIG. 3.

UNITED STATES PATENT OFFICE

1,996,564

FURNACE SEALING DEVICE AND GAS
CONTROL

Ovila J. Blanchet, New Bedford, Mass.

Application January 5, 1934, Serial No. 705,321

14 Claims. (Cl. 263—2)

This invention broadly relates to improvements in electric furnaces for heat treating purposes, and more particularly, the same has reference to an electric annealing furnace sealing means and 5 a gas control mechanism therefor.

In the art of heat treating the shanks of drills or the like, it is the practice to insert the shanks into either an electric furnace operable either on the inductance or resistance principle, and the 10 same heated in the presence of a non-oxidizing atmosphere to avoid discoloration of the tool. To accomplish this result, a gas is admitted to the respective heating chambers, and it is therefore the purpose of this invention to seal the 15 furnace openings when the tools are inserted therein to exclude the entrance of air from the heating chambers and to prevent the escape of the gas and heat from the heating chambers, and to automatically open the feed of the gas to 20 the heating chambers when the tools are inserted therein, and for shutting off the flow of gas to the chambers when the drills have cooled and are withdrawn.

Another object of the invention resides in an 25 electric switch means operable upon engagement of the drill holder with the electric furnace when a drill or gang of drills are inserted into the furnace for heat treating, for closing an electric circuit to open the gas valve to admit gas to the 30 drill heating chambers, the circuit being broken upon the withdrawal of the drill holder to cause automatic closing of the gas valve.

Another feature of the invention is the provision 35 of a sealing gasket for drill heating purposes having an opening normally greater than the diameter of the drill to be heat treated, and means for contracting the walls of the opening about the drill upon insertion of the same through the opening whereby to provide a tight seal between 40 the gasket and the drill.

With these and other objects in view, the invention resides in the certain novel construction, combination and arrangement of parts, the essential features of which are hereinafter fully described, are particularly pointed out in the appended claims, and are illustrated in the accompanying drawings, in which:

Figure 1 is a diagrammatic illustration of my 45 invention showing part in side elevation and part in section.

Figure 2 is a front elevational view of an electric 50 drill heating furnace showing my improved sealing gasket in position thereon.

Figure 3 is an enlarged vertical transverse section 55 view through an electric drill heating fur-

nace with the sealing gasket and circuit control switch in operative position.

Figure 4 is a fragmentary top plan view with parts broken away in section.

Figure 5 is a front elevational view of the drill 5 holder gasket.

Figure 6 is a rear elevation of the drill holder gasket.

Figure 7 is a rear elevational view of the furnace 10 sealing gasket.

Figure 8 is a front elevational view of the furnace sealing gasket.

Figure 9 is a perspective view of the furnace 15 sealing gasket member showing the two cooperating gasket sections in separated position, one of the sections having the gasket linings removed.

Figure 10 is an enlarged vertical sectional view 20 through the gas control valve.

In the art of annealing drill shanks and other 25 analogous articles, it is necessary to trap a non-oxidizing atmosphere in an annealing chamber and to insert and remove the drills to be annealed in such a way as to cause a minimum release of or interference with the atmosphere to avoid discoloration of the drills, which, from a commercial 30 standpoint is objectionable. The invention which will now be described aims to avoid the discoloration of these drills during an annealing process by sealing the drill receiving openings in the furnace and operates to control the flow of annealing gas to the annealing chambers in timed 35 relation with the insertion and withdrawal of the drills relative to the said chambers.

Referring to the drawings by reference characters, the numeral 10 designates a conventional 40 type of electric drill annealing furnace including a casing 11 having a plurality of spaced horizontally aligned heat treating or annealing chambers 12, suitably insulated from the casing and from each other by insulating material 13. The front 45 wall of the casing is provided with drill receiving openings 14 which communicate with the respective chambers 12, and which openings are of a diameter greater than the diameter of the drill shank to be annealed to facilitate the free insertion of the same into the chambers. Each chamber 12 contains a heating coil 15, the convolutions of which are greater than the diameter of the drills to be annealed and the same are disposed in axial alignment with the openings 14 and in 50 spaced relation to the walls of the chambers. The heating coils of the respective chambers are connected together in series and the same arranged in an electric heating circuit, not shown.

Entering each chamber 12 through the rear 55

thereof is a gas inlet pipe 16 connected to a gas supply pipe 17 which leads to a gas supply tank 18 containing nitrogen or other gaseous fluid used in the formation of a non-oxidizing atmosphere within the heat treating chamber. Arranged within the pipe line 17 for controlling the flow of gas therethrough is a control valve 19 the construction and operation of which will be herein-after explained.

10 Fixed to the exterior of the furnace casing 11 at the front thereof in axial alignment with each opening 14 is a furnace opening sealing gasket device 20. The sealing gasket device 20 includes a shell 21 of a di-electric material and comprises 15 a front wall 22 and a continuous flange 23 disposed at right angle to the front wall. Ears 24 formed integral with the shell 21 extend from opposite ends thereof through which screws or like fastening elements 25 pass for securing the device 20 in position upon the front of the furnace. The front wall 22 centrally thereof is provided with a relatively large opening 26 for the free passage of the drill to be annealed, while disposed at equal distance from the opening 26 20 on opposite sides thereof are two smaller size openings 27, the purpose of which will be explained hereinafter.

15 Fitting within the shell 21 for expansion and contractive movement therein are a pair of separate coacting metallic gasket members 28—28. Each gasket member 28 has a substantially semi-circular shaped body portion 29 terminating in outwardly extending hook shaped ends 30, the inner curved surfaces of the ends 30 constituting 20 seats 31 while the extreme flat surfaces 32 act as abutting stops for limiting the expansive movement of the members in their assembled position. The inner concave wall of the body portion 29 is provided with a groove or channel 33 to receive 25 and hold the rib 34 of a yieldable asbestos sealing lining 35. One side face of the body 29 of each member 28 is notched adjacent the hooked ends 30 as at 36, the depth of the notch being approximately one-half the thickness of the body where- 30 by the hooked ends may be crossed with the members in reverse positions as shown in Figure 7. The notches 36 are of a shape and size to permit contractive movement of the members 28 when in the normal expanded position shown in Figure 35 7 wherein the flat ends 32 thereof are in abutting engagement. The interior of the shell 20 is of a size and shape to snugly receive the coacting gasket members 28 with the outer sides of the body portions 29 of the said members abutting 40 the flange 23 of shell when expanded, while the hook portions 30 are at all times in spaced relation to the adjacent portions of the flanges. Engaging the outer curved surfaces of the hook portions 30 of the two gasket members are arcuate shoes 37 and interposed between the shoes and the adjacent spaced portions of the flange 23 are springs 38, which act to expand the body portions 45 of the members 28 and contract the hook portions thereof so that the coacting curved seats 31 form restricted passages in alignment with the respective openings 27 in the shell 20 as best seen in Figure 8. The shoe 37 of one of the sealing gasket devices has a threaded terminal post 39 connected thereto and which extends outwardly 50 through the shell and threadedly receives a clamping nut 40. In Figure 2 of the drawings, the terminal connector is provided on the left end gasket sealing device, for in a "gang" furnace it is only necessary that one of the sealing devices be so equipped.

5 For the purpose of holding one or a "gang" of drills to be annealed I provide a drill holder block 40 of di-electric and of a low heat absorbing material, the same being provided with a series of sockets 41 equal in number to the number of heat chambers of the furnace 10 and axially spaced relative to the furnace whereby the holder may be brought to an operative position with the sockets 41 in alignment with the respective openings 26 and 14. The drill holder 40 is also provided 10 with sealing gasket devices 42 attached to that face onto which the sockets 41 open, and which devices are positioned about the respective openings. A description of one of such sealing devices 42 will suffice for the others and the same 15 will now be described.

10 Each sealing device 42 comprises a metallic shell or casing 43 somewhat similar in shape to the shell or casing 21 and having a rear wall 44 and a continuous right angularly disposed flange 20 45. The rear wall 44 is provided with a central opening 46 similar in size to that of the opening 26, while extending from opposite ends of the casing are ears 47 having openings therein through which fastening elements 48 pass and enter the 25 holder block 40. One of the ears 47 is extended and supports a terminal post 49 to which a clamp- 30 ing nut 50 is threaded. Nested within the shell or casing 43 is a filler 51 of di-electric material and secured in position therein by two contact 35 studs 52, each stud having an enlarged conical head 53 and a reduced shank 54 fixed to rear wall 44 of the metallic shell 43. The studs are respectively disposed on opposite sides of a central opening 55 which is slightly larger in diameter than the opening 46 but in axial alignment therewith. The wall of the opening 55 is provided with a groove 56 in which the rib 57 of an asbestos or other yieldable heat insulating gasket 58 is seated and held. The studs 52 are so spaced 40 that they axially align with the openings 27 when the holder sealing device 42 is brought into operative engagement with the coacting furnace sealing device 20 in a manner and for the purpose 45 hereinafter explained.

45 The control valve 19 hereinbefore mentioned comprises a casing 59 having a cylindrical bore 60 opening to the atmosphere at the top end through openings 61 and by an opening 62 at the bottom. Arranged within the casing for 50 sliding movement in the bore 60 is a valve head 63 having a transverse passage 64 adapted to be moved into alignment with the pipe line 17 which enters the casing 59 to open the line, and to be moved out of alignment therewith to shut off the supply through the pipe line. A valve actuating 55 rod 64' has one of its ends fixed to the valve head 63 and while its opposite end is provided with an enlarged iron core 65 forming part of an electric solenoid 66. An arm 67 extends from the core 60 65 and has pivotal connection with one end of a rocker arm 68, pivoted intermediate its ends upon the top of a standard 69, the other end of the rocker arm having a counter balance weight 70 supported therefrom. The weight 70 serves 65 to normally hold the core 65 and valve head 63 in a raised position, and with the passage 64 out of registration with the pipe line 17, or in closed position. The solenoid 66 is arranged in an electric circuit with a source of electrical energy, one 70 end of the solenoid winding being connected by a wire 71 to the terminal 49 of one of the holder sealing devices 42 while the other end of the solenoid winding is connected by a wire 72 leading to the source of electrical energy. A wire 73 also 75

leading to the source of electrical energy is connected to the terminal post 39. It will therefore be seen that the holding sealing device 42 contacts with a mating furnace sealing device 20 to provide an electrical switch for closing the solenoid unit to energize the solenoid 66 and draw the core 65 inwardly to move the valve head 63 to open position, the opening movement of the valve head being limited by contacting engagement with a stop flange 74 within the casing 59.

In operation of the invention, assume that it is desired to anneal the shanks of a "gang" of drills of a particular diameter. The cutting end of each drill A is inserted into a socket 41 of the holder block 40, the said end first passing through the gasket 58 of the holder sealing device 42. The diameter of the gasket 58 is slightly smaller than the diameter of the drill so that upon insertion, the gasket will yield upon insertion of the drill and snugly embrace the drill at its entrance to the socket. After arranging the drills in the respective sockets of the holder with the shank ends extending therefrom, the holder is brought into position adjacent the furnace 10 as shown in Figure 1, whereupon the extending drill shanks are aligned with the openings in the furnace sealing devices 20, whereby the shank ends may be inserted into the respective heat annealing chambers, it being understood that the sealing gasket sections 28-28 are in a normally expanded position to facilitate the free insertion of the drill shanks therethrough. As the drill shanks near the end of this movement to a full inserted position, the conical heads 53 of the contact studs 52 pass through the openings 27 in the casing 21 and engage the seats 31 of the hooked ends of the members 28, the said seats normally coacting to provide a restricted passage for the contact studs. The beveled surfaces of the conical heads engage the seats and continued inward pressure thereon causes the hooked ends to be wedged apart, which action causes the body portions 29 of the members 28 to be drawn toward each other, whereupon the gaskets 35 are contracted about the drill shanks to tightly seal the interior of the annealing chambers from the atmosphere to prevent entrance of atmospheric air therein and to avoid loss of the non-oxidizing gas therefrom.

From the description thus far, it will be understood that the sealing devices 20 have all been contracted about the drill shanks and the furnace 10 is now ready for operation. The current to the heating coils 15 may be turned on to heat the annealing chambers. During the positioning of the drill shanks in the respective annealing chambers and the sealing of the chamber openings by the sealing devices 20, one of the studs 52 of the sealing device 42 containing the terminal post 49 has entered that sealing device 20 on which the terminal post 39 is mounted. Thus one set of mating sealing devices 20 and 42 when brought together act as a switch for closing the solenoid circuit, which causes the solenoid core 65 to be drawn inwardly of the solenoid and in turn actuate the rod to move the valve head 63 to open position against the action of the counter-balance weight 70. Opening of the valve 19 permits gas to flow from the tank 18 to the respective annealing chambers 12 and set up therein a non-oxidizing atmosphere about the drill shanks during the heat treating or annealing process. After the drill shanks have been subjected to the required heating, the same are left to cool and if desired, the supply of gas to the chamber 12 may be manually shut

off by the actuation of a hand valve 15 on the tank 18. After the drill shanks have been sufficiently cooled and assuming that the valve 15 is open, the operator draws the holder 40 away from the furnace 10 and withdraws the drill shanks therefrom. Just as soon as the heads of the studs 52 clear the seats 31, the springs 38 expand the members 28, thus releasing the same from about the drill shanks and returning the members to their normal position. As the electric contact stud of one of the sealing devices 42 is cleared from its engaging contact, the solenoid circuit is of course broken, which de-energizes the solenoid and allows the balance weight 70 to return the valve head 63 to its normal closed position.

While I have shown and described what I deem to be the preferred embodiment of my invention, I wish it to be understood that such changes and modifications may be resorted to as come within the scope of the appended claims.

Having thus described the invention, what I claim as new and desire to secure by Letters Patent of the United States, is:—

1. In a furnace for the treatment of an article or articles in the presence of heat and gases, a controlled gas supply for admitting gas to said furnace, means for sealing said furnace upon the insertion of an article therein to be treated, and means simultaneously operable by the insertion of the article in said furnace for admitting gas thereto.

2. In a furnace for the treatment of an article in the presence of heat and gases having an opening to the atmosphere, a controlled gas supply for admitting gas to said furnace, means for sealing said opening to the atmosphere upon the insertion of an article therethrough to be so treated, and means operable by the insertion of the article into said opening for admitting gas to said furnace.

3. In a furnace for the treatment of an article in the presence of heat and gases having an opening to the atmosphere, an electrically controlled gas supply for admitting gas to said furnace, means for sealing said opening to the atmosphere upon the insertion of an article therethrough to be so treated, and electric means operable by the insertion of the article into said opening for admitting gas to said furnace.

4. In a furnace for the treatment of an article in the presence of heat and gas having an opening to the atmosphere, a controlled gas supply for admitting gas to said furnace, an article holder for supporting the article to be inserted through said opening to be treated, and means operable by said article holder upon insertion of the article through said opening and into said furnace for admitting gas to said furnace.

5. In a furnace for the treatment of an article in the presence of heat and gas, an electrically controlled gas supply for admitting gas to said furnace, an article holder for supporting the article to be inserted through said opening to be treated, and electric switch means operable by the presence of said article holder adjacent said furnace for operating said electrically operated gas supply for admitting gas to said furnace.

6. In a furnace for the treatment of an article in the presence of a confined atmosphere having an opening to the atmosphere, a normally expanded adjustable sealing device mounted on said furnace about said opening, and means operable for contracting said sealing de-

- vice about the article after insertion of the same through said opening.
7. In a furnace for the treatment of an article in the presence of a confined atmosphere having an article receiving opening, a normally adjustable sealing device mounted on said furnace about said opening, an article holder adapted to support the article to be inserted through said opening and into said furnace, and cooperating means on said holder and said sealing device for contracting said sealing device upon the positioning of said holder adjacent said furnace to insert an article therein.
8. In a furnace for the treatment of an article in the presence of heat and gas having an article receiving opening, a sealing device mounted on said furnace about said opening, said sealing device including a pair of separated resilient normally expanded gasket members, an article holder for supporting an article to be inserted through said opening into said furnace, and cooperating means between said holder and said gasket members for contracting said gasket members about an article inserted into said furnace and held by said holder.
9. In a furnace for the treatment of an article in a confined atmosphere having an article receiving opening larger in size than the article to be inserted therethrough, a gasket sealing device mounted on said furnace about said opening, said sealing device including a pair of separable semi-circular shape complementary gasket members coacting to provide a sealing gasket, the ends of said gasket members terminating in oppositely turned hook portions, the ends of the gasket members being crossed to cause the same to coat and provide a pair of restricted openings, spring means acting upon said gasket members to normally expand the same and to cause the ends of the hook portions to abut, an article holder, a sealing gasket device mounted on said article holder, said last mentioned sealing device including a pair of spaced beveled studs of a size greater than the normal size of the openings formed by the hooked ends of the gasket members for wedging engagement with the walls of the said last openings to spread the hooked ends apart and simultaneously contract the gasket members about an article supported by said holder when inserted through the first mentioned sealing device and into said furnace.
10. In a furnace opening sealing device of the class described, a furnace opening sealing gasket including a pair of separate normally expanded resilient gasket members, a holder sealing gasket adapted to be brought into engagement with said
- furnace sealing gasket, and cooperating means between said gasket members and said holder sealing gasket operable upon bringing the two sealing gaskets together for contracting said gasket members.
11. In a furnace opening sealing device of the class described, a furnace opening sealing gasket including a pair of separate normally expanded resilient gasket members, a holder sealing gasket adapted to be brought into engagement with said furnace sealing gasket, and cooperating means between said gasket members and said holder sealing gasket operable upon bringing the two sealing gaskets together for contracting said gasket members, said cooperating means comprising crossed hooked ends on said gasket members to provide normally restricted openings, and conical studs on said holder sealing gasket for reception in said restricted openings for wedging engagement with the walls thereof to expand said hooked ends and simultaneously contract said gasket members.
12. A sealing gasket device comprising a shell having an opening therein, attaching means on said shell, a filler nested within said shell having an opening therein in axial alignment with said first mentioned opening but of the same or less diameter, and a yieldable gasket secured to the walls of said last mentioned opening and projecting inwardly thereof.
13. In a furnace for the treatment of an article in the presence of heat and gases having an opening to the atmosphere, a controlled gas supply for admitting gas to said furnace upon the insertion of an article therein to be treated, and means operable by the insertion of the article through said opening for admitting gas to said furnace.
14. In a furnace for the treatment of an article in the presence of heat and gases having an opening therein to the atmosphere through which an article to be treated is adapted to be inserted, expandable and contractible sealing means for sealing said opening after the insertion of an article therethrough, a gas supply for said furnace, a normally closed electromagnetically operable control valve for said gas supply, a normally open electric circuit in which said electromagnetic valve is arranged, and electric switch means in said electric circuit operable when the sealing means is in contracted position for closing said electric circuit to actuate said electromagnetic valve to "on" position to admit gas to said furnace.

OVILA J. BLANCHET.
